(57) CLAIM

The ornamental design for a pen, as shown and described.

DESCRIPTION

FIG. 1 is a lower front left perspective view of a pen showing my new design;

FIG. 2 is a front elevation view thereof;

FIG. 3 is an enlarged top plan view thereof;

FIG. 4 is a rear elevation view thereof;

FIG. 5 is a right side elevation view thereof;

FIG. 6 is an enlarged bottom plan view thereof; and,

FIG. 7 is a left side elevation view thereof.

The broken lines shown on the top of the pen in FIG. 3 illustrate environment and form no part of the claimed design.

1 Claim, 3 Drawing Sheets

Fig.1.
